UNITED STATES PATENT OFFICE.

CHARLES E. DELAPLAIN, OF JACKSONVILLE, ILLINOIS.

DESIGN FOR A DEFLATING IMPLEMENT.

47,877.

Specification for Design.

Patented Sept. 28, 1915.

Application filed February 12, 1915. Serial No. 7,901. Term of patent 14 years.

To all whom it may concern:

Be it known that I, CHARLES E. DELAPLAIN, a citizen of the United States, residing at Jacksonville, in the county of Morgan and State of Illinois, have invented a new, original, and ornamental Design for Deflating Implements, of which the following is a specification, reference being had to the accompanying drawing, forming a part thereof.

The figure is a perspective view of a deflating implement, showing my new design.

I claim:

The ornamental design for a deflating implement, as shown.

CHARLES E. DELAPLAIN.

Witnesses:

W. S. GRAY,
ALBERT BRASI.
